United States Patent Office.

JACOB E. RICE, OF MOLINE, ILLINOIS, ASSIGNOR TO HIMSELF AND CHARLES H. REMINGTON, OF SAME PLACE.

Letters Patent No. 106,205, dated August 9, 1870.

DRIER.

The Schedule referred to in these Letters Patent and making part of the same.

I, JACOB E. RICE, of Moline, in the county of Rock Island and State of Illinois, have invented certain Improvements in Dry-Houses, of which the following is a specification.

Nature and Objects of the Invention.

My improvement consists in the arrangement of the furnace outside of the dry-house, and connected with the smoke-stack by external and internal flues, whereby the draught, and consequent degree of heat, within the dry-house, may be regulated or shut off, as desired, and the heat of the furnace utilized for various purposes, without opening the dry-house.

It also consists in so arranging the education-pipe, whereby the heated vapors of the dry-house escape, so as to utilize the same for other heating purposes, or, by a connection with the smoke-stack, to increase the draught in the fire-flues, and also to induce a more rapid circulation of the heated air through the dry-house; and, also, in providing, within the dry-house, a perforated metallic shield over the interior flues, thereby dividing the interior into two compartments, in the lower one of which the freshly-admitted air is heated before passing into the upper or drying-chamber, to the walls of which it is directed by another shield, constructed in the manner and for the purpose as hereinafter fully set forth.

Description of the Accompanying Drawing.

Figure 1 is a perspective view of a dry-house, with my improvements.

Figure 2 is a horizontal sectional view on the plane of the line *x x*, fig. 1.

Figure 3 is a vertical sectional view on the plane of the line *y y* of fig. 1.

General Description.

A represents the dry-box, with the roof somewhat elevated in the center.

B represents an air-chamber, separated from the dry-box A, above it, by two shields, C and D, the lower shield, C, perforated or pierced with numerous holes, and curved, and placed with its concave side downward, its edges extending out to the walls of chamber B.

Immediately over the shield C is another, D, made entire, curved, and placed with its concave side upward, its edges not quite reaching to the walls of the chamber A.

E is a fire-box, just outside of and adjoining the chamber B, and provided with a hole and lids, e, on which a wash-boiler, or other vessel, may be placed.

G is a horizontal flue, extending from the fire-box E through the length of chamber B, and returning, by a continuation, G', to the outside of box B, where it connects with the chimney H.

I is a flue, connecting the fire-box E and flue G', as shown, and is provided with a valve, i.

J is a pipe, leading from the apex of the roof of the dry-box, and is provided with a valve, j.

K is a horizontal pipe, leading from the pipe J to the chimney H, and is provided with a valve, k.

L L are trays, with perforated bottoms, for holding fruit, when the dry-house is used for drying the same, ledges, l l, and bars, l' l', being arranged for the purpose of holding the trays in position.

One side of the box A may be provided with doors, for convenience of access to the inside thereof.

The operation of my invention is as follows:

The fire is made in the fire-box or furnace E, and the flame and heat, passing through the pipe G, will be returned through the pipe G'. The greater portion of the heat, in passing through said pipes, will be thrown, by radiation, into the chamber B, and the smoke, and unconsumed products of combustion, will be carried up the chimney H. The bottom of the chamber B, being pierced, will admit the outward air, which, being heated by the radiation from pipes G G', will ascend through the shield C, and, striking the shield D, be deflected and thrown out against the walls of the drying-chamber A, from whence it may pass freely to all parts of said chamber, its appetite, as may be said, for moisture being so increased by heating that it will sap the dampness from fruit, or other articles therein. The dampness, in the form of vapor, rising to the top of the roof, will pass out through the pipe K, the draught through which may be increased by connecting it with the chimney H; the valve in the pipe J being closed; or, said warm vapor and heated air may be passed up through the pipe J, and made to warm a room above, through which it may lead, by closing the valve k and opening the valve j.

When the device is used for drying fruit, ledges may be attached to the walls, as shown, on which bars may be laid for holding trays, on which the fruit may be placed, and which are perforated in their bottoms for the free admission and circulation of the heated air.

For drying clothes, &c., any suitable devices may be arranged for holding them in position to admit the passage of the air.

By opening the valve i, the current of heated air and smoke will be drawn direct to the chimney H, and, of course, withdrawn from the pipes G G'.

The lid e may be lifted, when desired, and a boiler, or other vessel, placed in the opening, for the purpose of heating water, or for other purposes.

Sad-irons, &c., may be heated by setting them on the top of the furnace E.

This arrangement of the furnace outside of the dry-house, it will be seen, thus not only enables the heat to be turned from the pipes G G' at will, but also af-

fords facilities for utilizing the heat from the furnace for various purposes.

Claim.

I claim as my invention—

The chambers A and B, furnace E, pipes or flues G G' and I, shields C and D, chimney H, pipes J and K, and valves k, j, and i, fruit-trays L L', ledges l l'

and bars l l', when combined and arranged to operate substantially as described, and for the purpose specified.

JACOB E. RICE.
